ABSTRACT: A mechanism for preparing the lead wires of a fluorescent lamp for receiving the lamp base by performing a search, gather and set operation on the lead wires. The lamp is fed into a position with the spaced lead wires separated by a lead wire guide and spacer plate and situated adjacent a fixed sandwich plate. A movable sandwich plate is pivoted toward the fixed sandwich plate until it abuts the spacer plate which separates the two sandwich plates by a distance only slightly greater than a lead wire diameter thus gathering the lead wires into substantially the same plane. A pair of cam operated setting blades then slide between the sandwich plates forcing the lead wires against the edges of the spacer plate to thereby set the lead wires in a straight and parallel condition for receiving the lamp base.

LEAD WIRE PREPARATION FOR THREADING FLUORESCENT BASES

BACKGROUND OF THE INVENTION

This invention relates to fluorescent lamp making equipment and more particularly to a mechanism for preparing the outwardly extending lead wires on a partially fabricated fluorescent lamp in anticipation of receiving the lamp base or end cap.

During the various operations required in the manufacture of a fluorescent lamp prior to the threading onto the extending lead wires of the base member or end cap the outwardly extending lead wires are caused to be moved, bent and disturbed during handling in a manner which often leaves them in a skewed relationship. It is desirable that these outwardly extending lead wires be both straight and substantially parallel when the lamp reaches a point in the manufacturing process where the base members are threaded onto each end of the lamp. The basic difficulty with present day equipment which may take the form of counterrotating brushes or clam shell-like gripping mechanisms, which may or may not include comb teeth on the ends thereof, is that they have not performed satisfactorily for the reason that bends previously placed in the wires during manufacture are extremely difficult to remove and when the lamp reaches the base threading head there is difficulty in finding the wires and even though the wires are on a correct centerline distance the base mounting equipment has difficulty in pushing the base down onto leads which are often neither straight, parallel nor vertical.

One solution to this problem is disclosed in U.S. Pat. No. 3,286,323 to E. Bastiaanse issued Nov. 22, 1966. To employ this device the lead wires must be previously cut to a selected length and be in a reasonably parallel relationship. In addition, this operation also contemplates the direct application of the end cap or base in conjunction with the lead wire preparation which may not in all cases be desirable.

SUMMARY OF THE INVENTION

It is an object of this invention to provide a mechanism by which a search, gather and set action can be applied to the outwardly extending lead wires of a fluorescent lamp.

Another object of this invention is to set the lead wires on a fluorescent lamp in such a manner that they will stand vertical and parallel to each other to facilitate the reception of a fluorescent lamp base.

A still further object of this invention is to provide a method whereby the lead wires extending from a partially fabricated fluorescent lamp may be set in a vertical and parallel relationship in preparation for receiving a fluorescent lamp base.

These and other objects are accomplished in accordance with the present invention by providing, in a mechanism for gathering and setting a pair of skewed lead wires of a fluorescent lamp into a straight and parallel relationship; a first plate member which has a raised spacing member on the face thereof which extends from the first plate member a distance slightly in excess of the diameter of the lead wires and has a lateral dimension approximately equivalent to the space between said lead wires at their juncture with the lamp. A second plate member is movable into engagement with the raised spacing member to define a planar channel on each side of the spacing member between the faces of the first and second plate members in which the lead wires are confined. A pair of oppositely disposed blade members are movable into the planar channels between the first and second plate members to force the lead wires disposed in each channel against the edge of the raised spacing member to thereby set the lead wires in a straight and parallel relationship.

BRIEF DESCRIPTION OF THE DRAWING

The foregoing objects, and others, along with many of the attendant advantages of the present invention will become more readily apparent and better understood when the following detailed description is considered in connection with the accompanying drawings in which:

FIG. 1 is an isometric view of the lead wire preparation mechanism of the present invention with portions of the mechanism broken away for purposes of clarity;

FIG. 2 is a side elevation view of a portion of the mechanism of the present invention with the pivotal sandwich plate in an open position;

FIG. 3 is a side elevational view, partially in section, of the mechanism of the present invention similar to the FIG. 2 embodiment with the pivotal sandwich plate in a closed position;

FIG. 4 is a front elevational view of the lead wire straightening mechanism of the present invention with the pivotal sandwich plate in a closed position;

FIGS. 5 and 6 are front elevational views similar to FIG. 4 with the sandwich plates removed to better illustrate the operation of the cam actuated setting blades.

DESCRIPTION OF THE PREFERRED EMBODIMENT

Referring now in detail to the drawings, wherein like reference characters represent like parts throughout the several views, there is shown in FIG. 1 an isometric view of the lead wire preparing mechanism of the present invention. As illustrated in phantom in FIG. 1, a fluorescent lamp generally designated 10 and having a pair of skewed or bent lead wires 11 and 12 extending therefrom will proceed along a fluorescent lamp assembly line to a point where the lead wires must be prepared for receiving a base or end cap. Although the lead wire straightening mechanism of the present invention will be shown and described with respect to the preparation of lead wires on one end of a fluorescent lamp tube, it should be understood that lead wire straightening is required on both ends of the fluorescent lamp and that the equipment of the present invention or like equipment can operate on each end one end at a time or duplicate equipment can be provided to operate on both ends simultaneously.

During the fabrication of the fluorescent tube, the outer lead wires are generally caused to be skewed or bent by the manufacturing operations and they must be oriented in a straight and parallel configuration prior to receiving a fluorescent base. As illustrated in FIG. 2, when a fluorescent lamp 10 is indexed from position A to position B the lead wires 11 and 12 will generally be bent or skewed in a direction away from the direction of travel indicated by the arrow and also away from each other. As the fluorescent tube reaches position B, the sandwich plate mechanism which includes a fixed sandwich plate 14, having a lead wire guide member 16 and a spacer plate or anvil 18 on the face thereof, will be in a raised position, having released the previous lamp, as illustrated in FIG. 2. Movable lamp gripper arm 20 will be in the position illustrated in phantom in FIG. 4. The movable sandwich plate 22 is mounted for slight pivotal movement in a yoke 24 on one end of the bellcrank 26 which is pivotally mounted on the sandwich plate frame 28 as shown at 30 in FIG. 2. Adjustable push rod 32 is connected at one end to the other arm of bellcrank 26 and at its other end to actuating lever 34.

As best illustrated in FIG. 1, operating rod 36 is connected through a yoke type pivot to the end of operating lever arm 38 which is at its other end pivotable about a shaft 40 fixed to the frame 42 of the machine. A second push rod 44 is pivotally mounted to operating lever 38 at 46 (FIG. 4) and includes a spring overtravel mechanism 48, the function of which will be later described. The other end of push rod 44 is pivotally connected to one end of L-shaped arm 50 which is pivoted proximate its midpoint at 52 to the machine frame 42 and which at its other end carries movable lamp gripper 20.

A second operating lever arm 52 is also pivoted at its end 54 about shaft 40 and carries at its other end, in a yoke type pivotal fashion, a second operating rod 56. The operating rod 56 has affixed at its one end, the setting blade mechanism generally designated 60 (FIGS. 5 and 6) which includes a yoke member 62 having pivotally mounted thereon at 64 a pair of downwardly extending blade carrying arms 66. At the other end of arms 66 are mounted a pair of oppositely disposed setting blades 68. The arms 66 are urged toward each other

about their pivot points 64 by a spring 70 and held apart by a pair of rollers 72 coacting with cam surfaces 74 which are a part of the machine frame 42.

In operation, the fluorescent tube generally designed 10 moves from the A position of FIG. 2 to the B position by means of the indexing conveyor (not shown) which carries the fluorescent bulb from one work station to another in the fabrication process. As indicated previously, when the fluorescent tube is in position B the sandwich plate mechanism is in a raised position as illustrated in FIG. 2 having just released therefrom the preceding fluorescent tube in the production cycle. At this point operating lever arm 38 is activated by a drive mechanism (not shown) which causes it to pivot about rod 40 thus moving operating rod 36 in a downward direction causing lead wire guide 16 to descend between the lead wires 11 and 12 until the notched-out edge portion 15 on the underside of sandwich plate 14 (FIG. 1) contacts and slightly depresses the upper edge of the bulb 10 causing it to move slightly downwardly in the releasable gripping mechanism (not shown) by which the fluorescent tubes are carried on the lamp indexing mechanism. As the operating rod 36 descends, as will be best seen in FIG. 4, push rod 44 descends a lesser extent causing movable gripper arm 20 to engage the lamp tube 10 while the spring overtravel 48 prevents excessive pressure from being applied to the wall of the fluorescent tube thus preventing breakage of the tube by the gripper arm as it forces the tube against fixed tube gripper 21 which is mounted to the frame 42 as shown in FIG. 1. With the sandwich plate mechanism in the FIG. 3 position but open as illustrated in FIG. 2 the operating lever arm 34 is now actuated by the drive mechanism (not shown) causing crank arm 26 to pivot about its pivot point 30 through the downward movement of push rod 32 causing movable sandwich plate 22 to pivot against spacer plate or anvil 18 thus substantially imprisoning lead wires 11 and 12 in planar slots on either side of spacer plate 18 between the sandwich plates 14 and 22.

The lead wires 11 and 12 now lie as illustrated in FIG. 3 between the sandwich plates 22 and 14 and have been gathered into substantially a single plane. With the sandwich plate mechanism in this position the setting blade mechanism is in the position illustrated in FIG. 5 with the cam rollers 72 in contact with the portion 74a of cam surface 74 and the setting blades 68 positioned with the lead wire engaging edges 69 disposed beneath the upper end of the fluorescent tube 10. At this point in the operation of the mechanism operating lever arm 52 is raised by a drive mechanism (not shown) causing operating rod 56 to rise thus lifting the setting blade mechanism in an upward direction. As the setting blade mechanism rises, cam rollers 72 carried by the arms 66 which are urged toward each other by spring 70 first ride along cam surfaces 74a so that the blades are held a sufficient distance apart to clear the edges of the fluorescent tube 10. As operating rod 56 continues to rise and setting blade mechanism 60 continues to rise with it, the cam rollers 72 coact next with the cam surfaces 74b and start to move slightly toward each other as the setting blades 68 enter the planar slot between sandwich plates 14 and 22. As the setting blade mechanism nears the top of its stroke, cam rollers 72 ride lastly on cam surfaces 74c and the setting blades 68 move rapidly toward each other carrying with them lead wires 11 and 12 until the lead wires are forced against the side edges of spacer plate 18.

The lead wires 11 and 12 are now both parallel and straight and are spaced apart a distance substantially equivalent to the width of the spacer plate or evil anvil 18. Operating lever arm 52 is now reversed in its direction of travel and the setting blades 68 removed from the planar slot between the sandwich plates 14 and 22. Lever arm 34 is now raised causing the movable sandwich plate 22 to move away from its engagement with spacer plate 18 and during this same motion operating rod 36 is also raised, lifting fixed sandwich plate 14 to a position above the top ends of the lead wires 11 and 12 while movable gripper arm 20 is also removed. The fluorescent lamp with its lead wires 11 and 12 in a straight and parallel configu-

ration is now freed from the lead wire straightening mechanism and may be moved out of position B of FIG. 2 while the next succeeding lamp is indexed from position A to position B.

As will be apparent, the width of spacer plate 18 is fairly critical and must be designed so that when setting blades 68 force the lead wires against the edges of the spacer plate, compensation is made for the slight spring back inherent to a greater or lesser extent depending upon among other things the resiliency and gage of the wire. Slight deviation from a truly straight and parallel configuration is of course permissible since the openings in the base or end cap through which the lead wires are eventually threaded are of a substantially greater diameter than that of the lead wires.

As will be seen from the foregoing, the lead wire straightening mechanism of the present invention provides a quick and accurate method for rendering the lead wires of a fluorescent tube both straight and parallel in preparation for receiving the end cap or base which is placed onto the ends of the fluorescent lamp during the next succeeding fabrication step.

Although a specific embodiment of the present invention has been illustrated and described, it will be apparent that numerous changes may be made without departing from the spirit or scope of this invention and it is intended that all matter contained in the foregoing description or shown in the accompanying drawings shall be interpreted as illustrative and not in a limiting sense.

1. Claim:

1. A mechanism for gathering and setting a pair of skewed lead wires of a partially fabricated fluorescent lamp to a straight and parallel relationship comprising:
 a first plate member having a raised spacing member on the face thereof, said raised spacing member extending from the face of said first plate member a distance slightly in excess of the diameter of said lead wires and having a lateral dimension approximately equivalent to the space between said lead wires at their juncture with the lamp;
 a second plate member having a face portion thereon and movable into engagement with said raised spacing member to define a planar channel between the faces of said first and second plate members in which a lead wire is confined on each side of said raised spacing member;
 a setting blade device including a pair of oppositely disposed blade members movable into said planar channel between said first and second plate members to force a lead wire disposed in said channel against the edge of said raised spacing member to thereby set said lead wires in a straight and parallel relationship.

2. The mechanism defined in claim 1 wherein said setting blade device is connected to a setting blade device operating rod and includes resilient means urging said blade members into said channel and cam means restraining said blade members from movement into said channel in response to the urging of said resilient means.

3. The mechanism defined in claim 2 wherein said resilient means is a spring interconnecting said oppositely disposed blade members and said cam means includes a roller fixed to each of said blade members and associated cam surfaces on said mechanism whereby said blade members are urged into said planar channels by said interconnecting spring as said rollers move along said associated cam surfaces in response to vertical movement of said operating rod.

4. A mechanism for gathering and setting a pair of skewed lead wires of a partially fabricated fluorescent lamp into a straight and parallel relationship comprising:

a frame;
 first and second sandwich plates having facing face portions mounted on said frame for movement with respect thereto;
 a raised stop member on the face portion of at least one of said sandwich plates;

means operable to cause relative movement between said sandwich plates to thereby bring the face portions of said sandwich plates into a predetermined spaced relationship to thereby define a planar channel therebetween; and blade members movable into said planar channel toward said raised stop member to thereby render said lead wires both straight and parallel.

5. The mechanism defined in claim 4 wherein said blade members are urged toward each other by an interconnecting spring means and including means associated with said blade members and said frame for controlling the rate of movement of said blade members into said planar channel under the influence of said spring means.

6. The mechanism defined in claim 5 wherein said means associated with said blade members and said frame include a

cam roller on each of said blade members and an associated pair of cam surfaces on said frame.

7. The method of gathering and setting a pair of skewed lead wires of a partially fabricated fluorescent lamp into a straight and parallel relationship for receiving a lamp base comprising the steps of:

gathering the lead wires into substantially the same plane by confining each lead wire within a separate three-sided compartment through the movement of one of said sides toward a second of said sides; and thereafter setting the lead wires in a straight and parallel relationship within said compartments by moving a fourth side of each of said compartments toward the third side of each of said compartments.
